UNITED STATES PATENT OFFICE

2,561,767

HAND WEAVING LOOM

Henry Adler, Detroit, Mich., assignor of one-half
to Lillian Holm, Bloomfield Hills, Mich.

Application January 11, 1950, Serial No. 138,057

9 Claims. (Cl. 139—29)

1

The object of my improvement is to raise the efficiency of the loom as a whole, to improve certain elements of which the loom is composed, and to render the attendance to certain functions preliminary to the operation of the loom much more convenient. Specifically, the object of my improvement is to provide a more efficient warp beam, an arrangement whereby the warp beam may be pivotally hinged to the frame of the loom, a novel and useful arrangement whereby the heddles used in the loom may be threaded conveniently, and novel means used in conjunction with the warp beam for keeping the warp threads on the beam under tension.

These and other improvements will now be shown with reference to the accompanying drawings, in which:

Fig. 1 is a side view of my improved loom;
Fig. 2 is a top plan view of the loom;

Fig. 3 is an end view of the loom as seen in the direction of the arrow "x" in Fig. 1;

Fig. 4 is a sectional view of an operative part of the loom on line 4—4 of Fig. 1;

Fig. 5 is a partly sectional view on line 5—5 of Fig. 4;

Fig. 6 is a sectional view on line 6—6 of Fig. 4;

Fig. 7 is an end view towards the warp beam of my loom as seen in the direction of arrows 7—7 of Fig. 4;

Fig. 8 is a sectional view on line 8—8 of Fig. 4;

Fig. 9 is a perspective view of a fragment of a warp beam with a tubular shaft and other operative elements therein;

Fig. 10 is a perspective view showing the disposal of warp threads over the lease sticks of the loom;

Fig. 11 is a perspective view of an accessory equipment for the loom for easy access to the heddles used therein;

Fig. 12 is a perspective view of said equipment shown with respect to the operative parts of the loom;

Fig. 13 is a sectional view on line 13—13 of Fig. 12;

Fig. 14 is a sectional view on line 14—14 of Fig. 1;

Fig. 15 is a sectional view on line 15—15 of Fig. 14;

Fig. 16 is a sectional view on line 16—16 of Fig. 14;

Fig. 17 is a fragmentary perspective view of an operative part of the loom shown in Fig. 14;

Fig. 18 is a perspective view of a calibrated reed holder used in the loom;

Fig. 19 is a sectional view taken on line 19—19 of Fig. 3.

2

Similar numerals refer to similar parts throughout the several views.

The framework of the loom is made of metal, preferably of metal tubing, and results in a compact but strong construction, including two front legs 10 and two rear legs 11 and 11a, each leg being joined to the leg rearwardly therefrom by a strut 12, said strut being in a spaced relation to floor 13 on which the loom is located. Integrally connected to each rear leg is a horizontal top member 14 of the frame, said member being joined to a vertical standard 15 turned over at the top to form a horizontal arm 16. The lower end of the standard is mounted on the respective strut 12, as is best shown in Fig. 1. Mounted upon leg 11a is a bracket 17 including two horizontal ears 18. Journalled within said ears is a vertical pin 19, the lower end thereof being hollowed, as shown at 20, and threaded internally for reception of a bolt 21 passing through the aperture in the lower ear 18 of bracket 17. A sleeve 22 fits over said pin 19 and between ears 18, and includes, midway its length, a horizontal integrally formed shank 23. Telescopically fitting over the shank and supported thereby is a tubular shaft 24 which forms an axial element of a warp beam generally indicated by numeral 25. The beam is made in the form of a hollow cylinder, including an outer shell 26 and two circular plug-like end closures 27 and 28. Each closure is provided with a flange, 29 and 30 respectively, and with a central opening serving as a bearing for shaft 24. One of said end closures, namely, closure 27, is in a face to face abutment with a ratchet wheel 31 which is axially seated upon said shaft 24 and welded thereto, as shown at 32, for rotation with said shaft. A pawl 33 pivotally affixed to flange 29 and urged into engagement with the teeth of the wheel by a spring 34 permits rotation of the shaft in one direction only. Closure 28, at the other end of the beam, is provided with ratchet teeth 35, while a pawl 36, pivotally mounted on leg 11, is designed for engagement of said teeth and to control the rotation of the beam with the shaft therein. The rotary movement of the beam with the shaft may be effected by means of a manually-operated driving wheel 37 provided with radial handles 38. The wheel is secured in place upon the end of the shaft remote from shank 23 by means of a pin 39 passing diametrically through said shaft, as best shown in Fig. 4.

As already described, the warp beam 25 is supported by shaft 24, which, at one end, is connected by means of a shank to sleeve 22. At

the opposite end the shaft rests in a fragmentary or open bearing 40 mounted on leg 11, as best shown in Fig. 7. The bearing is in the nature of a supporting lug from which the shaft may be readily removed by being slightly raised upwardly to clear a hump 41, whereupon the shaft with the beam 25 may be swung away from said leg 11. Embracing shaft 24 within beam 25 is a plurality of annular clamps 42 disposed in a spaced relation to each other to permit rotation of the shaft therewithin. Each clamp carries an eye member 43 which projects therefrom radially, as best shown in Fig. 8. The shell 26 of warp beam 25 has a number of aligned pairs of openings 44, as best shown in Figs. 4 and 8, the pairs being spaced with respect to each other to correspond to the spacing of clamps 42. A cord 45 knotted to the shaft close to one end closure of beam 25 is wound around the shaft, as shown in Fig. 4, then passes through the first eye member 43, as shown in Fig. 9, and is drawn outwardly through one opening 44 in the first pair of said openings. Formed into a loop 46, the cord is returned through the other opening 44 of the same pair, is rethreaded through eye 43, as shown at 45a, and is carried towards the next clamp. Here said cord again passes through an eye member 43, and so on, and forms another loop 46 in the manner already described. Altogether, as many such loops are formed as there are clamps 42. The opposite end of the cord, after having formed the last loop 46a, is free to be wound again about shaft 24 and to be knotted thereto to prevent displacement thereof.

Loops 46 serve as connecting means to a horizontal bar or stick 47, the stick in turn serving as a means to which individual warp threads 48 may be tied, as shown at 49. Carried upwardly, warp threads 48 pass over a horizontal stretching beam 50, the ends of which are journaled at 50a within the horizontal top members 14 of the framework. The warp threads are drawn in the conventional manner through lease sticks 51 and 52 disposed parallel to each other transversely to the direction of the threads. The arrangement requires that every second thread should pass over the first stick and under the second stick, while every other thread should pass initially under the first lease stick and over the second one, as best shown in Fig. 10. Guiding means for the lease sticks include two flexible cables 53, each being, at one end, anchored to an eyelet 54 mounted on the horizontal top member 14. Each cable is removably mounted at its other end to one end of the nearer lease sticks, that is, lease stick 51, as shown in Figs. 2 and 10. Short lengths of cable 55 connect the lease sticks in parallel relation to each other.

As in the course of the weaving the warp is subjected to what is known as shedding when certain threads of the warp are made to assume an angular position with respect to other threads, the customary practice requires that the individual threads be controlled by heddles 56 and 56a. The heddles are suspended at the top from harness sticks 57 and 57a respectively, the harness sticks being suspended by means of cords 58 from two-armed heddle horses 59 and 59a, respectively. Each horse depends from a separate cord 60, each cord passing over a separate pulley 61. The pulleys are mounted on a shaft 62 journaled at its ends in standards 15. After having passed over its pulley, each cord supports at its opposite end another heddle horse 59a, which in turn holds up a harness stick 57a with

a plurality of heddles 56a tied thereto. At the lower end heddles 56 and 56a are tied to another pair of sticks 63 and 63a, respectively, each heddle being provided with an eye 68 or 68a, as the case may be. Vertical movement of the heddles tied to the respective sticks 57 and 63 or 57a and 63a may be effected by means of pedals 64 within the lower portion of the framework. The pedals are connected by intermediate means, 65, 66, and 67 and 65a, 66a, and 67a, to the lower harness sticks 63 and 63a, respectively. As the construction is well known, details thereof are omitted. The respective warp threads passing through eyes 68 and 68a, respectively, may now be shifted up or down as required in shedding by means of said pedals 64.

While in the above description only two sets of heddles were shown, the actual number of sets of heddles may vary according to the nature of the textile material to be produced. In all such cases the threading of the eyes is a tedious procedure made inconvenient by reason of the position of the heddles within the framework of the loom. To simplify said procedure and to make the heddles more accessible, I have devised supplementary equipment shown in Figs. 11, 12, and 13. The equipment includes a gate composed of a vertical cylindrical member 69 provided with an axial socket 70 to fit over the upper end 19a of shaft 19, already described herein and best shown in Figs. 1, 4, and 12. Radially extending from said cylindrical member 69 in the same direction at two different levels are two rails, a top one 71 and a lower one 72. The rails 30 may be made of one length of stock which is looped back upon itself, as shown at 73. For rigidity the rails are kept in their spaced relation by a plurality of vertical struts 74. It will be noted that the warp beam 25 is mounted directly below the gate, that is, directly below rails 71 and 72, parallel thereto, and that shaft 24, which supports said beam, is also disposed radially and connected by intermediate means to the same shaft 19. As a result thereof, the beam and the gate swing horizontally from said shaft as a unit.

Slidably mounted on the upper rail 71 of the gate are two racks 75, each of the racks including a horizontal arm 76 having, at one end, a hook-shaped member 77 to fit over the top rail, while the lower portion of said member bears against the lower rail 72. Each arm has a plurality of transverse slots 78, the slots in one arm being aligned with those of the other. Said slots serve for reception of harness sticks 57, described above, before said sticks are suspended from heddle horses 59, as set out hereinabove. Suspended from the lower rail 72 by means of short links 79 is a stretching bar 80. Individual harness sticks may be supported within the respective pair of slots 78 in said racks, with the heddles 56 depending therefrom, as shown in Fig. 12, and held extended by the weight of the lower harness sticks 63. A pin 81 may be thrust into the arm lengthwise through a bore 82 so that the pin will pass across slot 78 and through holes 83 in the harness sticks 57. While the heddles are in the position just above-described, individual warp threads 48 may be conveniently threaded through eyes 68 of said heddles, as best shown in Fig. 12. Once this has been done, the racks 75 may be lifted with the whole gate off the upper end of shaft 19 and mounted upon a short pin 84 upon the horizontal top member 14 of the framework, as shown in Fig. 11. Here the tubular member 69 of the gate will fit over said pin

84, while the opposite end of the gate, specifically, the lower rail 72, will fit into a slotted retaining member 85 mounted on member 14 of the frame.

It will be noted that in Fig. 12 the warp threads 48 are shown broken off, as at 86. It is at about this position of the threads that the lease sticks 51 and 52 are located when the heddles are to be threaded, as shown in Fig. 10. For that purpose the lease sticks would be first disconnected from cables 53, shown in Fig. 10. In Fig. 12 the lease sticks have been omitted to avoid confusion in presentation of the novel features of the supplementary equipment shown in said figure.

Another novel feature of my improved loom pertains to a combined reed and beater, generally identified by numeral 87. The device comprises two parallel and vertically-spaced rails 88, the rails being U-shaped in cross-section, the open side of one rail being opposed to the open side of the other rail. Said rails are connected by two upright rods 89 disposed crosswise at the respective ends of said rails. At the upper end the rods are joined to a horizontal shaft 90 supported at each end within one of the notches 91 in a horizontal bar 92 on top of arm 16 of standard 15. A counter-weight 93 keeps the beater-reed combination at a slightly inclined angle away from the operator of the loom, who is sitting at the end remote from the warp beam, as best shown in Fig. 1. Slidingly disposed between rails 88 is a reed 94 made in the conventional form, that is, a reed including a rectangular frame 95 and a plurality of close-spaced vertical wires 96 within said frame. Calibrations 97 upon the lower rail, on the outside surface thereof facing the operator, serve to guide the operator's centering of the reed.

The textile material made on the loom by means of a shuttle in the usual manner will pass over a breast beam 98 journaled within the top portions of legs 10 over a knee beam 99 journaled within the framework at a level below the breast beam, and will be wound upon the cloth beam 100 journaled within bearings 101 supported at each side of the loom on a cross-member 102 extending between leg 10 and the standard 15 on said side, as best shown in Fig. 1. The cloth beam is analogous in structure to that of the warp beam, and includes a cylindrical shell 103 closed at one end by closure 104 and by closure 105 at the other end. The closures include centrally-located bearings 106 and 107, respectively, for a tubular shaft 108 which is disposed axially within the shell, as best shown in Fig. 14. Projecting at each end beyond the body of the shell, the shaft rests in bearings 101 already mentioned herein. A wheel 109 provided with spokes or handles 110 is mounted at one end of the shaft and is secured thereto by means of a pin 111 diametrically passing through said shaft. A plurality of bolts 112, each terminating with an eye at 113, are secured to the shaft 108 and serve as intermediate means for passage of a cord 114. The ends of the cord are tied to the shaft, as shown at 115 and 116, respectively, while a number of loops 117, formed by said cord, intermediate its ends, serve as connecting means to rope stick 118. It is to the latter that individual warp threads 48 are tied in the manner described with reference to the warp beam. To permit loops 117 to be brought partly outwardly of the shell, the latter is provided with holes 119 analogous to holes 44 in the warp beam.

Still another novel feature has been designed by me for use with the warp beam. This is shown

in Figs. 3, 9, and 19. It pertains to a normally rolled-up sheet of pliable material, said sheet being designed to separate strands of threads of warp as said warp is wound upon the warp beam. Here are the details of the construction: A roller 120, similar to that used for shades, and including a coiled-up spring 124, is journaled at its ends within brackets 121 mounted upon legs 11 and 11a of the framework of the loom below the warp beam. Wound upon the roller is a sheet 122 of pliable material which may be of textile or plastic nature, the outer end portion of the sheet being provided with hooks 123. The hooks fit into openings 44 in the shell of the warp beam and serve as means for attachment of the sheet to said beam. As the beam is rotated in the direction of the arrow shown in Fig. 9 threads 48 of the warp will be sandwiched between layers of the rolled-up sheet, as shown in Fig. 19. The sheet will keep the warp threads in one layer separate from the threads of another layer, aiding in maintaining even tension upon said threads. Should it be required, it would be an easy matter to add to the sheet another one by clamping it or by hooking it to the first-mentioned sheet.

The manner in which the warp beam may be used is as follows: individual threads of the warp may be tied to stick 47. For convenience, the stick may be drawn away from the surface of the warp beam. This may be accomplished by disengaging pawl 33 from the teeth of the ratchet wheel 31 which is seated upon shaft 24, whereupon cord 45 wound upon said shaft may be unwound, permitting loops 46 to be drawn out through openings 44 in the shell of the beam. The operation results in the rotation of the shaft within the beam while the beam itself remains stationary. When the warp threads have been secured to stick 47 the rotation of the shaft may be reversed by means of the ratchet wheel in order that the loops of cord 45 be withdrawn into the beam until stick 47 bears against the surface thereof. Now, to wind the warp upon the beam, said beam, with the shaft, may be rotated by means of the driving wheel 37. In the course of making cloth, that is, in the final stages of the operation when the warp is unwound and drawn through heddles towards the cloth beam, stick 47 may again be pulled away from the surface of said warp beam and gradually drawn up to the level of the horizontal members 14 of the framework of the loom. This eliminates waste of the length of warp which otherwise would extend from the warp beam to the level of said members 14.

If it is desired to separate the layers of the warp as it is wound up, this may be accomplished by means of the pliable sheet of material normally rolled up on the roller 120 in a manner already described above and illustrated in Figs. 3, 9, and 19.

Other novel features, like for instance the calibrated frame of the beater and the structure of the cloth beam, have been described in the course of this specification and it is believed that the manner of their use is quite obvious.

It will be understood that some changes may be made in the structure of the several improvements described herein without departing from the inventive principle disclosed by me.

What I, therefore, wish to claim is as follows:

1. In a handloom including a framework, as described, a warp beam comprising a cylindrical shell, a plug-like closure within each end thereof,

a tubular shaft axially disposed within the shell and projecting outwardly through said closure at each end of the shell, said shell being provided with a plurality of openings spaced from each other and arranged in a line parallel to the axis of the shell, a cord at one end tied to the shaft within the shell adjoining one end closure, said cord passing through the openings outwardly therefrom, a plurality of loops for connection to a bar disposed parallel to the shell for attachment of warp threads thereto, the other end of the cord being tied to the shaft within the shell adjoining the other end closure, means to rotate the shaft within the shell, and means to rotate the shell, the shaft being adapted to be rotated about its axis within the shell, means to rotate the shell and the shaft as a unit, and a pawl and ratchet arrangement at one end of the shell permitting the rotation by the above-said means of the shaft alone.

2. In a handloom including a framework, as described, a warp beam comprising a cylindrical shell, a plug-like closure within each end thereof, a tubular shaft axially disposed within the shell and projecting outwardly through said closure at each end of the shell, a plurality of clamps on the shaft, each clamp including an eye in a radial relation to the shaft, the clamps being spaced from each other and loosely mounted on the shaft to permit the rotation of the shaft therewithin, said shell being provided with a pair of openings opposite the eye of each clamp, a cord tied to the shaft within the shell adjoining one end closure, said cord passing consecutively through each eye outwardly through one opening in a pair of openings opposite said eye and forming a loop by passing back through the other opening of said pair and through the same eye and being tied to the shaft within the shell adjoining the other end closure thereof, bearings on the framework for each end of the shaft, means to rotate the shaft with the shell, the shaft being adapted to be rotated about its axis within the shell, means to rotate the shell and the shaft as a unit, and a pawl and ratchet arrangement at one end of the shell permitting the rotation by the above-said means of the shaft alone.

3. In a handloom including a framework, as described, a warp beam comprising a cylindrical shell, a plug-like closure within each end thereof, a tubular shaft axially disposed within the shell and projecting outwardly through said closure at each end of the shell, a plurality of clamps on the shaft, each clamp including an eye in a radial relation to the shaft, the clamps being spaced from each other and loosely mounted on the shaft to permit the rotation of the shaft therewithin, said shell having openings opposite the eyes of the clamp, a cord tied to the shaft within the shell adjoining one end closure passing consecutively through the eye of each clamp and outwardly through the opening in the shell to return back to the shell through the same respective eye, thus forming a loop for connection to a horizontal bar for attachment of warp threads thereto, means to support the shaft at each end, a ratchet wheel keyed to the shaft adjoining one end closure of the shell, a pawl mounted on the last said closure for engagement with said ratchet wheel for control of the rotation of the shaft, manual means to disconnect the pawl from said ratchet wheel, ratchet means at the other end of the shell to control the rotation of said shell and the shaft as a unit, and means to support

the shaft at each end for rotation thereof about its axis.

4. A warp beam as described in claim 3 and pivotal means at one end of said warp beam to allow it to be swung from said end horizontally away from the framework of the loom.

5. In a loom including a framework, as described, in combination a warp beam at the end of the framework, means whereby the warp beam is pivotally supported at one end of said framework and is adapted to be swung away in a horizontal plane from said end, two horizontal rails extending above and parallel to the warp beam, the rails being spaced from each other in a vertical plane, rack means mounted on the rails transversely thereto and a plurality of heddles suspended by intermediate means from said rack means, said rails being adapted to swing with the warp beam as a unit.

10 6. In a handloom including a framework, as described, a warp beam at one end pivotally mounted upon a vertical pin affixed to said framework, a gate above the warp beam, said gate being also pivotally mounted at one end 25 upon the above vertical pin and extending parallel to said warp beam, a pair of horizontal racks removably mounted on said gate transversely thereto, the racks being adapted to support by intermediate means a plurality of heddles, said 30 gate being adapted to be swung horizontally from its pivotal end together with said warp beam.

7. In a combination of elements as set forth in claim 6, a pair of racks comprising horizontal arms, each of the arms being provided with a 35 plurality of transverse slots for reception of harness sticks disposed parallel to the warp beam and supporting a plurality of heddles suspended therefrom.

8. In combination with a warp beam of the 40 kind described, a roller mounted for rotation parallel to said warp beam, a length of pliable fabric substantially co-extensive in width with the length of said warp beam, said fabric being rolled upon said roller, means at the outer end of said 45 fabric for attachment to the surface of the warp beam, the fabric being adapted to be wound upon the warp beam to separate layers of warp thereon, and spring means within the roller to roll up said pliable fabric upon the roller as said fabric is 50 un wound from the warp beam.

9. In combination with a warp beam of the kind described, a roller mounted for rotation parallel to said warp beam, a length of pliable fabric substantially co-extensive in width with the length 55 of said warp beam, said fabric being rolled upon said roller, and means at the outer end of said fabric for attachment to the surface of the warp beam, the fabric being adapted to be wound upon the warp beam to separate layers of warp thereon.

60 HENRY ADLER.
